UNITED STATES PATENT OFFICE.

RAY S. WEAVER, OF MONMOUTH, ILLINOIS.

FEED-TROUGH.

1,242,399.

Specification of Letters Patent.

Patented Oct. 9, 1917.

Application filed August 10, 1916. Serial No. 114,254.

To all whom it may concern:

Be it known that I, RAY S. WEAVER, a citizen of the United States, residing at Monmouth, in the county of Warren and State of Illinois, have invented certain new and useful Improvements in Feed-Troughs, of which the following is a specification.

This invention relates to improvements in feeding and watering troughs, more particularly to devices of this character constructed wholly of metal, and has for one of its objects to improve the construction and increase the efficiency and durability of devices of this character.

With these and other objects in view, the invention consists in certain novel features of construction, as hereinafter shown and described and then specifically pointed out in the claims; and in the drawings illustrative of the preferred embodiment of the invention—

Figure 1 is a side elevation, partly in section, of the improved device;

Fig. 2 is a transverse section on the line 2—2 of Fig. 1;

Fig. 3 is a plan view, with a portion in section on the line 3—3 of Fig. 1.

Corresponding and like parts are referred to in the following description and indicated in all the views of the drawings by the same reference characters.

The improved device comprises a body portion 10, preferably semi-circular transversely and of any suitable length and constructed of sheet or plate metal pressed or bent into the required shape. The edges of the body 10 are folded, as shown at 11, to stiffen and strengthen the edges, the edges being connected by a plurality of transverse stays 12 spaced apart and riveted or otherwise secured to the edges 11, as shown at 13. The stays 12 will be attached to the rims 11 at suitable intervals, preferably about 12 inches apart, the number depending on the length of the trough. The body 10 is provided with outer end members 14 with the upper and lower edges directed inwardly, as shown at 15—16, the inwardly directed portions being folded to produce two thicknesses of the material, as shown at the left of Fig. 1. By this means, the flange portions 15—16 are materially stiffened and strengthened, and are riveted or otherwise secured, as shown at 15—16, respectively, to the edges 11 and the bottom portion of the body 10. The body 10 is provided with obliquely di-

rected channels or grooves 18 at the ends, the channels or grooves being produced by a suitable implement or beading tool or machine in the material of the body.

Inserted within the channels 18 are inner end members, represented at 19, the upper edges of the members 19 being seated in the space between the adjacent end of the folded over portions 15, and formed sufficiently large to provide for springing the member 19 into the channel 18. By this means the members 19 are held firmly in their seats in the channels. If the trough is to be employed for liquid foods, the inclined or sloping members 19 will be soldered or otherwise rendered liquid tight relative to the body 10. The inner inclined or sloping end members 19 perform a threefold function. First, they materially increase the strength of the trough; second, they coact with the outer end members 14 to resist the effect of concussions and jars and prevent injury from that source, and third, the upwardly and outwardly sloping forms of the inner end members prevent injury to the trough from frozen or partly frozen liquids.

All of the parts of the improved trough are of metal as light as possible consistent with the strains to which they will be subjected when in use, and may be manufactured almost entirely of machinery, thus decreasing the cost of manufacture and the labor necessary to assemble the parts. The improved trough is strong and durable, while at the same time, light and easily transported or shipped.

Having thus described the invention, what is claimed as new is:

1. A feed trough comprising a body having laterally directed side flanges, outer end members with flanges overhanging the body and engaging the side flanges of the same, said body having inwardly opening channels near the ends directed obliquely to the longitudinal plane of the body and terminating beneath the overhanging flanges of the ends, fastening devices operating through the flanges of the ends and of the body, and inner end members engaging in said channels and between the end members and the flanges thereof.

2. A feed trough comprising a body having outer end members with flanges overhanging the body, said body having inwardly opening channels near the ends directed obliquely to the longitudinal plane of

the body and terminating beneath the over-hanging flanges, and inner end members engaging in said channels and between the flanges and the outer end members.

5. A feed trough comprising a body, outer end members engaging the body with the upper edges of each end member directed at right angles to the ends to form an over-hanging flange with the inner portion of each flange folded upon itself to form a stop, said body having inwardly opening channels directed obliquely to the longitudinal plane of the body and terminating beneath the flanges, and inner end members engaging 10 at one edge between said stops and the outer end members with the remainder of the inner end members engaging respectively in said channels.

4. A feed trough comprising a body, outer end members with flanges overhanging the body and forming stops, and inner end mem- 20

bers bearing against the interior of the body and directed obliquely to the longitudinal plane of the same, the upper edge of the inner end member engaging between the outer 25 end member and the stop of the same.

5. A feed trough comprising a body having laterally directed side flanges, outer end members with flanges overhanging the body and engaging the side flanges of the same, 30 inner end members bearing against the interior of the body and directed obliquely to the longitudinal plane of the same, the upper edge of the inner end member engaging between the outer end member and the stop 35 of the same, fastening devices operating through the flanges of the ends and of the body, and means for fastening the obliquely directed inner end members to the body.

In testimony whereof I affix my signature. 40

RAY S. WEAVER. [L.S.]
